George Subick INVENTOR
BY Victor J. Evans ATTORNEY

UNITED STATES PATENT OFFICE

GEORGE SUBICK, OF CHICAGO, ILLINOIS

STORAGE APPARATUS

Application filed April 26, 1929. Serial No. 358,360.

This invention relates to certain novel improvements in storage apparatus and is particularly adapted for use in connection with clothing and the like and has for its principal object the provision of an improved construction of this character which will be highly efficient in use and economical in manufacture.

It is among the objects of my invention to provide a construction in which clothing may be stored so as to prevent dust accumulations thereon and prevent the same from becoming soiled.

Another object of the invention is to provide a construction of the above named character which will be arranged in a manner such that different types of clothing hangers may be associated therewith and which will embody supporting means which may be arranged to be adjustable.

Another object of the invention is to provide a construction of the above named character which will be arranged so that it may be positioned in a closet or such that it may be arranged on a suitable supporting skirt at any desired point.

A further object of the invention is to provide a device of the above named character in which a covering member of flexible material may be employed.

Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a front elevational view depicting a preferred form of construction for my invention;

Fig. 2 is a top plan view of the hanger member employed in my device;

Fig. 3 is a side elevational view of the device as depicted in Fig. 2;

Fig. 4 is a view drawn to an enlarged scale depicting the arrangement of the hanger structure on a suitable supporting structure;

Fig. 5 is a sectional view taken substantially on the line 5—5 of Fig. 2;

Fig. 6 is a sectional view taken substantially on the line 6—6 of Fig. 2;

Fig. 7 is a detail plan view of a connection employed in the device;

Fig. 8 is a sectional view taken substantially on the line 8—8 on Fig. 7;

Fig. 9 is a detail view depicting a connection employed at the corner structures; and

Fig. 10 is a side elevational view of the device as depicted in Fig. 1.

In the accompanying drawings wherein I have illustrated a preferred form of construction for my invention 10 and 11 indicate the side plates of my improved hanger structure. Arranged at corresponding ends 65 of the side plates 10 and 11 are corner structures 12 and 13 and arranged at opposite corresponding ends of the side plates 10 and 11 are corner structures 14 and 15 which are of greater length than the corner structures 12 70 and 13 as is clearly depicted in Fig. 3. In the corner structures 12 and 14 adjacent the upper ends thereof openings are provided into which the rod 16 is extended. In a similar manner a rod 17 extends between the upper 75 ends of the corner structures 13 and 15. Disposed in the wall at right angles to the wall in which the rod 17 extends in the corner structure 15 an opening is provided into which a rod 18 is extended and the rod 18 is 80 arranged so that it will extend into the corner structure 15 in a manner such that the end portion thereof will fit into a recess 19 formed in the end of the rod 17 as is clearly depicted in Fig. 9. The opposite end of the rod 18 similarly extends into the corner construction 14 and is connected to the rod 16 85 in the same manner as the opposite end thereof is connected to the rod 17. A similar rod 20 extends between the corner constructions 12 and 13 and is similarly connected to the rods 16 and 17 and in this manner the frame of the supporting structure is defined.

In each of the side frames 10 and 11 adjacent the corner structures hanger bars are attached. These hanger bars are attached in the following manner: In the side plate 10 slots 21 and 22 are formed. In the side plate 11 slots 23 and 24 are formed. The hanger bars are indicated by 25 and 26, the hanger 100

bar 25 extending between the side plates 10 and 11 at the ends thereof at which the slots 21 and 23 are disposed while the hanger bar 26 extends between the side plates adjacent 5 the ends having the slots 22 and 24 associated therewith. At each of the ends of the bars 25 and 26 I arrange a plate such as 27. Each plate has a lug such as 28 extending from one edge thereof adjacent one end in which a 10 restricted opening is provided. Bolt members such as 29 are extended through the slots and the opening in the lug 28 and are screwed into the adjacent ends of the bars 25 and 26 and in this manner the bars 25 and 26 are 15 clamped in position. In addition to the clamping attained by the bolt members 29 I arrange in the plate 27 a plurality of openings 30 in the portions thereof extending along the side plates and in the side plates adjacent 20 these portions I arrange the pins 31 each of which projects into a selected one of the openings 30 and in this manner the hanger bars 25 and 26 are supported in position. The hanger bars 25 and 26 are employed to support 25 a hanger such as that indicated by 32 in the drawings which include at the upper end a strip 33 which has hook portions 34 and 35 at the ends thereof and the hook portions 24 and 25 are disposed over the bars 25 and 26 30 and in this manner the hangers 32 are supported in position. The adjustability provided for the bars 25 and 26 is such that these bars may be positioned so as to be spaced apart in different amounts since hangers such 35 as the hanger 32 are made in different lengths and, therefore, the hook portions 34 and 35 will be spaced apart in different amounts on different hangers and, therefore, since the bars 25 and 26 are adjustable these different 40 length hangers may be expeditiously arranged in the device.

At substantially the midpoint in the extent of the side plates 10 and 11 I provide up-standing plates 36 and 37 which are secured to 45 the side plates in any approved manner. Extended between these plates 36 and 37 is a hanger bar 38. In Fig. 7 I have depicted the manner in which the hanger bar 38 is secured to the side plate 36. An opening 39 is 50 provided in the side plate 36 through which the adjacent end of the bar 38 is projected and a bolt 40 is threaded into the screw threaded opening 31 in the end of the bar 38. In a similar manner the bar 38 is connected to the side 55 plate 37. The bar 38 is employed to support clothes hangers such as that indicated by 42 in the drawings which has a hook structure 43 extending upwardly therefrom substantially midway between the ends thereof.

60 A reenforcing rod 44 extends between the side plates 36 and 37 and as is clearly illustrated in Fig. 8 the ends of this reenforcing rod are extended into suitable openings in the side plates. Clips such as 45 are provided 65 which have openings therein through which

the rod 44 is extended and the clips 45 include hook portions which fit over either the rod 16 or 17 and in this manner the reenforcing rod 44 serves to properly brace the structure.

At the upper ends of the corner structures 12 and 13, 14 and 15 I mount resilient portions 70 which in the present instance are substantially hemispherical in shape and which are made from a pliable material such as vulcanized rubber and these portions are indicated by 46.

Extending upwardly from the vertical plates 36 and 37 are hook structures 47 and 48. The hook structures 47 and 48 are intended to be fitted over a suitable horizontal support 49 which may be for example a transverse rod in a closet or which may be supported by vertically extending standards 50 and 51 which have the relatively wide foot portions 52 associated therewith as is clearly illustrated in Figs. 1 and 10. When this latter structure is 75 employed it is readily apparent that the device may be mounted at any desired point.

The supporting structure hereintofore described is intended to support a suitable fabric member which will provide a housing. 80 This fabric member includes a top portion which rests on the resilient portions 46 and includes side walls which depend from this top portion and a suitable bottom is provided to extend between the side walls. One of the 85 side walls of this fabric structure is made in two portions indicated by 53 and 54 which are intended to be joined together in any approved manner as to the use of buttons or any other desired connecting means. If a button 90 structure is employed it is preferable that an additional strip indicated by 55 be associated with one of the portions 53 or 54 interiorly thereof along the edge intended to join the other portion and in this strip 55 the button holes will be provided while the buttons will 95 be secured on the edge of the other of the portions.

It is apparent from the foregoing description that I have provided an expeditious construction in which clothes may be mounted so as to be kept free from dust and the like and I have arranged this device in a manner such that it may be expeditiously arranged at any desired point.

100 While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A supporting frame including side plates having slots formed therein adjacent 115

the ends thereof, parallel bars extending between said side plates, connecting plates at the ends of said parallel bars, attaching means extended through the slots in said side plates and into the ends of said bars through said connecting plates whereby to secure said parallel bars to said side plates, said connecting plates having a plurality of aligned openings therein, studs on said side plates whereby said studs on said side plates may be selectively inserted through said openings to retain said connecting plates and said parallel bars in predetermined positions with respect to each other.

2. A supporting frame including side plates having slots formed therein adjacent the ends thereof, parallel bars extending between said side plates, connecting plates at the ends of said parallel bars, attaching means extended through the slots in said side plates and into the ends of said bars through said connecting plates whereby to secure said parallel bars to said side plates, said connecting plates having a plurality of aligned openings therein, studs on said side plates whereby said studs on said side plates may be selectively inserted through said openings to retain said connecting plates and said parallel bars in predetermined positions with respect to each other, corner structures at the ends of said side plates, and bars extending between said corner structures adjacent the upper ends thereof.

3. A supporting frame including side plates having slots formed therein adjacent the ends thereof, parallel bars extending between said side plates, connecting plates at the ends of said parallel bars, attaching means extended through the slots in said side plates and into the ends of said bars through said connecting plates whereby to secure said parallel bars to said side plates, said connecting plates having a plurality of aligned openings therein, studs on said side plates whereby said studs on said side plates may be selectively inserted through said openings to retain said connecting plates and said parallel bars in predetermined positions with respect to each other, corner structures at the ends of said side plates, bars extending between said corner structures adjacent the upper ends thereof, and means for connecting said bars in said corner structures.

4. A supporting frame including side plates having slots formed therein adjacent the ends thereof, parallel bars extending between said side plates, connecting plates at the ends of said parallel bars, attaching means extended through the slots in said side plates and into the ends of said bars through said connecting plates whereby to secure said parallel bars to said side plates, said connecting plates having a plurality of aligned openings therein, studs on said side plates whereby said studs on said side plates may be selec-

tively inserted through said openings to retain said connecting plates and said parallel bars in predetermined positions with respect to each other, corner structures at the ends of said side plates, bars extending between said corner structures adjacent the upper ends thereof, means for connecting said bars in said corner structures, and pliable members at the upper ends of said corner structures.

5. A supporting frame including side plates having slots formed therein adjacent the ends thereof, parallel bars extending between said side plates, connecting plates at the ends of said parallel bars, attaching means extended through the slots in said side plates and into the ends of said bars through said connecting plates whereby to secure said parallel bars to said side plates, said connecting plates having a plurality of aligned openings therein, studs on said side plates whereby said studs on said side plates may be selectively inserted through said openings to retain said connecting plates and said parallel bars in predetermined positions with respect to each other, corner structures at the ends of said side plates, bars extending between said corner structures adjacent the upper ends thereof, means for connecting said bars in said corner structures, and means arranged intermediate the ends of said side plates for supporting said side plates and the portions secured thereinto from a supporting structure.

6. A device of the class described including side members having slots formed therein adjacent the ends thereof, parallel members extending between said side members, connecting members at the ends of said parallel members, attaching means extended through the slots in said side members and into the ends of said parallel members through said connecting members whereby to secure said parallel members to said side members, said connecting members having a plurality of aligned openings therein, projections on said side members whereby said projections may be selectively inserted through said openings to retain said connecting members and said parallel members in predetermined positions with respect to each other.

In testimony whereof I affix my signature.
GEORGE SUBICK.
